UNITED STATES PATENT OFFICE.

WILLIAM R. DALES, OF PHILADELPHIA, PENNSYLVANIA.

HAT-RETAINING DEVICE.

1,354,892.

Specification of Letters Patent.

Patented Oct. 5, 1920.

Application filed July 30, 1919. Serial No. 314,193.

To all whom it may concern:

Be it known that I, WILLIAM R. DALES, a citizen of the United States, residing at Philadelphia, in the county of Philadelphia and State of Pennsylvania, have invented 5 certain new and useful Improvements in Hat-Retaining Devices, of which the following is a specification.

My invention relates to improvements in 10 hat retaining devices employing a spring retaining member between the body of the hat and the sweat band for the purpose of holding the hat upon the head of the wearer thereof against the action of the wind and 15 other forces tending to displace it.

The object of my present invention is to 20 improve the efficiency of devices of this character, to provide a novel construction which may be used effectually in both soft 25 and stiff hats, and to provide a novel means for retaining the device in proper working relation to the parts of the hat.

With the above and related objects in view, my invention consists in the novel 25 construction and combinations of parts hereinafter described and claimed.

In the accompanying drawings, illustrating my invention,

Figure 1 is a top view of my improved 30 retaining device, removed from the hat.

Fig. 2 is a face view thereof.

Fig. 3 is a bottom view of a hat having the retaining device in place therein.

Fig. 4 is a vertical section through the 35 hat with the retaining device therein, on line 4—4 of Fig. 3.

Fig. 5 is a fragmentary sectional view of the hat on the line 5—5 of Fig. 3.

Referring to the drawings, 2 designates 40 the body of a hat and 3 the sweat band which extends around the inside of the hat body and has its lower edge portion attached to the bottom thereof by sewing or otherwise in the usual well known manner.

The retaining device shown in Figs. 1 and 45 2 is placed within the hat 2 between the forward part of the hat body and the adjacent part of the sweat band 3, as shown in Figs. 3 and 4, and it comprises a bearing member 4 and a retaining member or 50 device 6.

The bearing member 4 is formed of suitable metal and it comprises a long flat body portion 7 and retaining parts or tongues 8 55 formed on the top of the respective ends thereof and bent to extend inwardly and

downwardly therefrom so as to occupy positions parallel with but slightly spaced from the body portion 7, as shown in the drawings. The body portion 7 is shaped to 60 conform to and fit against the inside of the forward part of the hat body 2 and it is attached thereto by means of stitches 9 sewed through the hat body and through holes or openings 10 in the member 4. 65

The retaining device 6 is inserted between the body 7 of the bearing member 4 and the sweat band 3 and it is preferably formed of spring brass and comprises end members or arms 11 and an intermediate member 12 70 which connects the arms 11. The arms 11 are inserted between the body 7 of the member 4 and its retaining parts 8, and the retaining parts 8 are provided with indentations 13 which extend into the space between the parts 8 and the body 7 of the member 4 and prevent accidental endwise displacement of the device 6 relatively to the bearing member 4. 75

The retaining device 6 has spaced bearing parts 14 and an intermediate bearing part 15. The spaced bearing parts 14 are adapted to engage the bearing member 4, and the intermediate bearing part 15 is adapted to engage the sweat band 3, and 80 hold it normally spaced from the bearing member 4 and the hat body 2, as shown in Figs. 3 and 5. The arms 11 may rest in 85 slidable contact with the body 7 of the bearing member 4 or its retaining parts 8 or 90 both; and the arms 11 are free to slide toward and from each other between the body 7 and parts 8 as the central part 12 of the retaining device 6 is sprung toward and 95 from the central portion of the bearing member 4.

In assembling the parts, the bearing member 4 is first sewed to the hat body 2 in the position shown in the drawings, the forward portion of the sweat band 3 is then turned 100 down from within the hat body and the arms 11 of the retaining device 6 are slipped up into place between the body 7 of the bearing member 4 and its retaining parts 8, in the position shown in Figs. 3, 4 and 5, and thereafter the sweat band 3 is turned back into the position shown in the hat. In this position of the parts, the upper ends of the retaining arms 11 prevent accidental upward displacement and the sweat band 3 prevents 105 accidental downward displacement of the retaining device 6 from its position adjacent to

the bearing member 4 and between the sweat band 3 and the body of the hat 2, leaving the retaining device 6 free to slide against the bearing member 4 as the central portion of 5 the retaining device is sprung toward and from the forward portion of the hat body.

When the device is applied to the hat as shown in the drawings and described herein, and the hat is applied to the head of the 10 wearer, the central portion of the retaining device 6 is sprung from its normal position toward the front of the hat body 2, and, afterward, as it tends to resume its normal position, it presses against the head of the 15 wearer with a cushioning effect and prevents accidental displacement of the hat from the head.

The bearing member 4 is preferably formed of spring brass so that when the device is applied to a soft hat, the shape of the 20 bearing member 4 will follow the shape of the soft hat as it conforms to the head of the wearer when applied thereto, the bearing member 4 thus always forms a relatively 25 stiff and smooth bearing surface for the spring retaining device to work against. In addition to this, the metal forming the bearing member 4 is of greater stiffness than the body of the soft hat and thereby holds the 30 farward part of the hat body properly spaced from the retaining device 6 when the head of the wearer of the hat does not force the central part of the spring retaining device 6 into contact with the bearing member 35 4.

I claim:—

1. The combination with a hat body having a sweat band attached thereto, of a bearing member secured to the hat body between 40 it and the sweat band, and a spring retaining device between the body of the hat and the sweat band and having two spaced bearing parts slidably engaging the bearing member and an intermediate part spaced from the 45 body of the hat and the bearing member and engaging the sweat band.

2. The combination with a hat body having a sweat band attached thereto, of a bearing member secured to the hat body between 50 it and the sweat band and having retaining parts extending therefrom, and a spring retaining device between the body of the hat and the sweat band and having two spaced bearing parts slidably engaging the bearing member 55 and an intermediate part spaced from the body of the hat and the bearing member and engaging the sweat band, said retaining device being held in operative relation to said member by said retaining 60 parts.

3. The combination with a hat body provided with a sweat band having its lower edge attached to the bottom of the hat body, of a bearing member secured to the hat body between it and the sweat band and having 65 retaining parts connected at their upper ends to the bearing member and extending downwardly therefrom, and a spring retaining device between the body of the hat and the sweat band and having two spaced 70 bearing parts slidably engaging the bearing member and an intermediate part spaced from the body of the hat and the bearing member and engaging the sweat band, said retaining device being held in operative relation to said member by said retaining parts.

4. The combination with a hat body having a sweat band attached thereto, of a bearing member secured to the hat body between 80 it and the sweat band, a spring retaining device between the body of the hat and the sweat band and having two spaced bearing parts slidably engaging the bearing member and an intermediate part spaced from the 85 body of the hat and the bearing member and engaging the sweat band, and means to prevent endwise displacement of said device from its operative relation to the bearing member.

5. The combination with a hat body having a sweat band attached thereto, of a bearing member secured to the hat body between it and the sweat band, a spring retaining device between the body of the hat and the sweat band and having two spaced bearing parts slidably engaging the bearing member and an intermediate part spaced from the body of the hat and the bearing member and engaging the sweat band, and means to prevent vertical displacement of said device relatively to the bearing member.

6. The combination with a hat body having a sweat band attached thereto, of a bearing member secured to the hat body between 105 it and the sweat band, a spring retaining device between the body of the hat and the sweat band and having two spaced bearing parts slidably engaging the bearing member and an intermediate part spaced from the 110 body of the hat and the bearing member and engaging the sweat band, means to prevent endwise displacement of said device from its operative relation to the bearing member, and means to prevent vertical displacement 115 of said device relatively to the bearing member.

In testimony whereof I affix my signature hereto.

WILLIAM R. DALES.
